(57) **CLAIM**

The ornamental design for a brush, as shown.

DESCRIPTION

FIG. 1 is a front, top and left side perspective view of a brush.

FIG. 2 is a front, bottom and left side perspective view thereof.

FIG. 3 is a rear, top, and right side perspective view thereof.

FIG. 4 is a front elevation view thereof.

FIG. 5 is a rear elevation view thereof.

FIG. 6 is a left side elevation view thereof.

FIG. 7 is a top plan view thereof, with two inset enlarged detail views;

FIG. 8 is a bottom plan view thereof, with an inset enlarged detail view;

FIG. 9 is a front, top and left side perspective view of an alternative embodiment of a brush.

FIG. 10 is a front, bottom and left side perspective view of the design as shown in FIG. 9.

FIG. 11 is a rear, top and right side perspective view thereof.

FIG. 12 is a front elevation view thereof.

FIG. 13 is a rear elevation perspective view thereof.

FIG. 14 is a left side elevation view thereof.

FIG. 15 is a top plan view thereof; and,

FIG. 16 is bottom plan view thereof.

The broken lines in the drawings illustrate the portion(s) of the article being enlarged, as well as the bounds of the detailed enlargements views themselves. The broken lines form no part of the claimed design.

1 Claim, 16 Drawing Sheets
